DESIGN FOR A FROZEN CONFECTION

Harry W. Hahn, Los Angeles, Calif., assignor to Paul Hawkins Company, Los Angeles, Calif., a corporation of California

Application February 11, 1935, Serial No. 55,346

Term of patent 7 years

To all whom it may concern:

Be it known that I, Harry W. Hahn, a citizen of the United States, residing at Los Angeles, in the county of Los Angeles and State of California, have invented a new, original, and ornamental Design for a Frozen Confection, of which the following is a specification, reference being had to the accompanying drawing, forming a part thereof.

In the drawing:

Fig. 1 is a front elevational view of a frozen confection, showing my new design;

Fig. 2 is a side elevational view of the confection shown in Fig. 1, illustrating my new design; and

Fig. 3 is a top plan view of a frozen confection, illustrating my new design.

I claim:

The ornamental design for a frozen confection as shown.

Signed at Los Angeles, California, this 7th day of February, 1935.

HARRY W. HAHN.
